ATTY

UNITED STATES PATENT OFFICE.

ALPHEUS W. ALTOFFER, OF PEORIA, ILLINOIS.

WASHING MACHINE.

Application filed July 2, 1925. Serial No. 41,147.

This invention has reference to washing machines, and it has for its principal object to improve the dolly or agitating means, whereby to produce a more effective and improved washing action on the articles deposited in the tub or container thereof.

The invention has for a further object to provide a dolly or agitating member operative from and by means of a shaft passing up through the bottom of the tub or container, and so constructed with radially arranged fins or baffle members and an intermediate surface inclined or curved upwardly from its peripheral edge, that the resultant action of the dolly or agitator, as it is alternately oscillated is to cause the articles being washed to be moved toward the center of the dolly or agitating member and upwardly and thence outwardly and downwardly; or in other words, impart to such articles a slow whirl like motion radially of the dolly or agitator and thereby more effectively cleanse the articles, by constant agitation and the forcing of air and water through the articles.

A further object of the invention is to provide in a washing machine, an oscillatory dolly or agitator so constructed, that it will act upon the articles being washed in a way as to cause said articles to circulate or whirl slowly in a direction radially of the tub and from and toward the center of the tub with a limited circular movement circumferentially of the tub; the centrifugal action set up by the oscillation of the dolly or agitator tends, or causes the articles as they rise to or above the water line, to recede from the center of the tub, thereby aiding in the radial circulation of such articles.

A further object of the invention is to form or provide the bottom wall of the tub or container with a depressed annular seat to provide, in effect, a shroud for the lower base of the dolly or agitator and to prevent the articles being washed from getting thereunder and thereby becoming torn or otherwise damaged. And, to position the baffles or fins for active operation on the articles, near the water line, the base of the dolly or agitator is formed or provided with a comparatively deep annular flange or apron which extends down into the seat formed or provided in said bottom wall.

That the invention may be more fully understood, reference is had to the accompanying drawings forming a part of the present description, illustrating a preferred embodiment of the invention, in which:—

Figure 1 is an elevation, in section, showing a washing machine embodying my invention;

Figure 2 is a top plan view partly broken away and in section, and

Figure 3 is a detail plan, in section, as the same would appear on the line 3—3, Figure 1.

Like characters of reference denote corresponding parts throughout the figures.

The tub or container 1 is preferably cylindrical in shape, not unlike those in general use in machines of like character, except that it is made possible, with the use of a washing element, such as I show and describe, to provide a tub or container with a comparatively larger surface area than is ordinarily found in machines of this class. Said tub or container is supported by standards or legs 2, and the bottom wall 3 thereof is substantially flat, as at 4, and formed or provided with a centrally and annularly depressed seat portion 4' to provide a shroud for the dolly or agitator, to be described.

Extending upwardly through the bottom wall 3 of the tub is an operating shaft 5, and said shaft on its lower end has a gear 6 engaged by a rack or segment gear 7 connected to and adapted to be oscillated back and forth by a shaft 8. Connected to said shaft 8 is a crank 9 arranged to be operated by suitable means, not shown, from any suitable source of power. The gear wheel 6 and the rack or segment gear 7 may be encased in any suitable housing 10.

The shaft 5 extends up through and has bearing in a stem or casing 11, open at its upper end and to the upper end of said shaft 5 is connected a coupling member 12 having a depending flange 13 encircling the upper end of the stem or casing 11 and the extended axial portion of said member 12 is preferably square, as at 14, to provide a convenient mode of attaching the dolly or agitator, to be described, thereto, and to detach the same therefrom. The lower end of said stem or casing 11 passes through the bottom wall 3 of the tub or container, and any suitable

means is employed to seal the connection between said stem or casing and said bottom wall to prevent leakage around said stem or casing.

- 5 The dolly or agitator is designated 15 and comprises a preferably annular base portion including a comparatively deep annular flange or apron 16, which, when the dolly or agitator is assembled in the tub or container 10 extends part way down into the seat 4' formed or provided in the bottom wall 3, and upstanding from said base portion, is a preferably tapered tubular sleeve 17 having a shouldered throat 18 provided with a 15 square opening arranged axially therein to fit over the squared extension of the coupling member 12 connected to the shaft 5. Such a construction provides a simple means by which the dolly or agitator may be attached 20 to and detached from the shaft 5. The surface of the dolly or agitator, from its peripheral edge slopes inwardly and upwardly, as at 19, merging into the sleeve-like portion 17, forming in effect a central cone-like structure, and 25 20 is a spider or bearing arm securing to and within the dolly or agitator and to the underside of its sloping surface 19 to give it a proper bearing, in its lowermost portion, on the shaft 5, as shown. 30 Formed or provided on the upper surface of the base of the dolly or agitator, are a plurality of radially arranged upstanding major fins or baffles 21 which, as shown, extend inwardly from the peripheral edge of the dolly 35 or agitator and merge or fade into the sleeve-like portion 17. The upper portions of said fins or baffles are shown as curvel downwardly and inwardly and upwardly into said sleeve-like portion 17. Arranged immediately of certain of said major fins or 40 baffles 21 and disposed radially diametrically of each other, are a pair of supplemental fins or baffles 22, see Figure 2. The fins or baffles 22 extend longitudinally 45 of the sleeve-like portion 17, preferably to a suitable point above the top of the fins or baffles 21, see Figure 1 and project a short distance from said sleeve, as shown in Figure 2, and in operation tend to force the 50 articles being washed outwardly, whereas the combined action of the curved surface of the dolly or agitator and fins or baffles 21 is to draw the articles inwardly and upwardly of the dolly or agitator. Combined with these 55 actions is the centrifugal force set up by the oscillation of the dolly or agitator, which tends or causes the articles as they rise to or above the water line, to recede from the center of the tub, thereby aiding in the 60 radial circulation of such articles. Furthermore, it is to be understood that with this slow whirling or radial circulation of the articles, there is less chance of the articles becoming entangled and there is only a limited 65 circular movement of the articles circumfer-

entially of the tub and the articles thereby kept from being wound around the center stem or post of said dolly or agitator, as will be found in many of the different machines of this class.

70 As will be seen, the height to which the shaft 5 extends up into the tub or container 1 and the length or height of the dolly or agitator 16 which is carried thereby, inasmuch as it is supported from the upper end 75 of said shaft, will determine the position of the fins or baffles in the water in the tub, or container, and the relative positions of such fins or baffles to the normal water line in the tub; also the position of the base of 80 the dolly or agitator to the bottom wall of the tub. The post or stem connection formed between the shaft 5 and the dolly or agitator is such, that the upper end thereof is sufficiently far above the water, when 85 agitated, to prevent leakage through the top of said stem.

90 As will be understood, the annular depressed seat portion 4', formed or provided in the bottom 3 of the tub or container serves as a shroud for the base of the dolly or agitator and will prevent articles from getting under said dolly or agitator and becoming torn or otherwise damaged. Such a condition is furthermore prevented by the deep 95 apron on the base of the dolly or agitator which positions the upper surface of the base thereof above the normal flat surface 4 of the tub bottom; arrows indicating the 100 approximate movement of the articles in a radial direction toward and from the axis of the tub and over the curved surface of the dolly or agitator and the normal water line being indicated in its relation to the fins or baffles.

105 What I claim is:—

110 1. In a washing machine, a tub having a substantially flat bottom wall provided with a centrally disposed depressed annular seat forming a shroud for a dolly, a shaft passing up through the depressed portion of said bottom wall, a dolly removably and operatively connected with the upper end of said shaft and having its washing surface above the flat bottom portion of said bottom wall and provided with a depending and peripheral annular apron operative within 115 said shroud, and a plurality of radially arranged baffles upstanding from the washing surface of said dolly.

120 2. In a washing machine, a tub having a substantially flat bottom wall provided with a centrally disposed depressed annular seat forming a shroud for a dolly, a tubular stem passing up through the depressed portion of said bottom wall, an operating shaft within said stem, a coupling member connected to the upper end of said shaft above said stem, a dolly comprising an annular base and a tapered stem arranged for a de- 125 130

tachable operative connection with said coupling member, the washing surface of said base being normally above the flat bottom portion of said bottom wall and being curved upwardly and inwardly into said stem and said base including an annular depending peripheral apron arranged de-

pending and operative within said shroud, and a plurality of radially arranged baffles upstanding from the washing surface of said dolly.

In witness whereof, I have hereunto affixed my hand this 20th day of June, 1925.

ALPHEUS W. ALTORFER.
